ROTARY TYPE CAN OPENER

Robert E. McLean, Fort Benning, Ga.

Application January 18, 1944, Serial No. 518,760

18 Claims. (Cl. 30—15)

1

This invention relates generally to the class of cutlery and pertains particularly to improvements in devices for opening or removing the heads of cans or similar containers, more especially those devices of the rotary type.

The present application is based upon and presents improvements over my prior Patents No. 2,287,442 of June 23, 1942, No. 2,294,507 of September 1, 1942, No. 2,314,506 of March 23, 1943, and No. 2,411,449 of November 19, 1946 wherein, as in the present application, are shown rotary can opening devices constructed in a novel manner whereby a single hand turned element is employed to perform the functions of raising an inserted or applied can to a position where a cutting knife will penetrate the head thereof and then rotating such can with respect to the knife to effect the cutting out of such head, such functions being carried out through the provision of a novel thrust mechanism and novel escapement mechanisms with which latter the hand operated means or crank is initially coupled.

A particular object of the present application is to provide in a rotary can opener of the type generally described above, certain novel improvements in the escapement mechanism by which release of the hand operated means or crank for free rotation, after penetration of the head of a can has been effected by the cutting element, is effected.

Another object of the invention is to provide in a device of the character herein stated, a novel means of coupling together two opposed plates of the device whereby to securely lock such plates together and at the same time provide a bearing for a shaft of a driving wheel.

Another object of the invention is to provide in a rotary type can opener a novel movable head cutter which, when moved in one direction upon the turning of the hand operated means or crank, causes the cutting knife to penetrate the can head, the can driving wheel of this form, unlike the wheels of all previous forms, having rotary movement only.

The invention will be best understood from the following detailed description taken in connection with the accompanying drawings, with the understanding that the invention is not to be confined to any strict conformity with the showing of the drawings but may be changed or modified so long as such changes or modifications mark no material departure from the salient features of the invention as expressed in the appended claims.

In the drawings:

Figure 32 is a view in side elevation of another embodiment of trigger structure for the escapement mechanism.

Referring now more particularly to the drawings there is illustrated in Figures 1 to 4 a hand or portable can opener based upon the construction illustrated in Figures 13 to 18 inclusive of my Patent 2,314,506. In this form of opener the body plate is generally designated 1 and has at its upper end the lateral extension 2 with the outer or free edge of which is joined as an integral part, a head consisting of the upstanding wall 3, the horizontally extending short wall 4 and the outer depending wall 5 which has resilient connection with the opposed parallel wall 3 solely through the medium of the short horizontal intervening portion 4.

Secured to the inner side of the depending wall 5, by screws or other suitable means 6, is a cutter 7 having the downwardly directed oblique edge 8.

Formed through the plate 1 adjacent the top thereof is the longitudinally extending elliptical opening 9 and this slotted portion of the body plate is interposed between the inner and outer side wings 10 and 11 of a substantially U-shaped yoke which is generally indicated by the numeral 12.

The space between the inner and outer wings of this yoke is only slightly greater than the thickness of the plate 1 so that the latter is relatively snugly received therebetween.

The inner wing 10 of the yoke lies directly beneath the flange 2 of the plate 1 as shown in Figure 3 and formed integral with the lower edge of the inner wing 10 and inwardly offset with respect thereto and from the plate 1, is the depending link 13 which forms a part of a toggle spring coupling with the lower end of the body plate 1. Such coupling is formed between the inner ear 10 of the yoke and the fixed pivot pin 14 which is secured in the lower end of the body plate and projects inwardly therefrom.

Rotatably supported upon the pin 14 is a substantially C-shaped spring 15, the lower leg or extension of which is suitably apertured to receive the pivot pin 14 while the upper leg or extension, which is disposed between the link 13 and the plate 1, is pivotally coupled with the link 13 by the pivot pin or rivet 16. The said ends of the C spring have the inwardly turned opposed extensions 17, the end edges of which come into closely spaced relation as shown in Figure 2 so that relative movement between the ends of the spring is limited to a small amount.

The lower end of the link 13 below the pivot 16, is turned to form the narrow can rest flange 18 against which the side of a can bears when it is in position in the cutter.

The numeral 19 designates a combined bearing and coupling sleeve between the wings 10 and 11 of the yoke. This sleeve passes through the elliptical opening 9 as shown.

Figure 5 shows on an enlarged scale the manner in which the bearing sleeve 19 is secured to the two wings of the yoke, such wings here being designated 10a and 11a while the bearing sleeve 5 is designated 19a. As shown the sleeve has cut or formed therein near each end an encircling V channel 20. The outer edge of each wing opening in which the grooved end of the bearing sleeve is positioned, is pressed inwardly to form the bordering lip 21, the corner of which fits into the adjacent channel 20 of the bearing sleeve as shown thereby securely coupling the ends of the bearing sleeve to the adjacent wings and also firmly locking the wings together.

The bearing bushing or sleeve of Figure 5 is shown with each end extending beyond the outer face of the adjacent wing of the yoke. This construction is also shown in connection with the bearing bushing or sleeve 19 of the structure shown where it will be seen that the extended ends of the bushing perform the function of holding adjacent elements in spaced relation with respect to the outer or remote faces of the wings 10 and 11.

In Figure 6, however, is shown a slightly modified construction of the locking connection between an end of the bearing bushing or sleeve and a wing of a yoke corresponding to the yoke 12, where the end of the bushing is flush with the outer side of the wing to which it is attached. Here it will be seen that the impressed lip 21a encircling the opening in which the adjacent grooved end of the bearing 19b is mounted, is cut or pressed from the wing, here designated 30 11b, so as to lie inwardly from the plane of the outer face of the wing thereby allowing sufficient space between the plane of the outer face of the wing and the outer corner of the lip 21a for the short portion of the bearing sleeve between 35 the peripheral groove and the adjacent end thereof.

This improved bearing sleeve construction may be used in any of the structures shown in my prior patents as well as in the structures shown 45 in the present application. Also, it is to be understood that, while the improved bearing sleeve is shown in the openers of the present application, such openers are not limited to the use of this bearing sleeve but the swaged coupling sleeves of the prior patents may be used 50 if found desirable.

The bearing or bushing sleeve 19 of the cutter shown in Figures 1 to 4, carries an encircling collar 22 which extends through the opening 9 55 and is of a length to extend the full width of the space between the wings 10 and 11. This collar may be made separate from the bushing or as an integral part thereof as desired and its overall diameter is substantially equal to the width of the elliptical opening 9 so that it may smoothly rotate therein and also move lengthwise thereof.

In Figures 5 and 6 the collar, shown as a separate part although it may be formed in one piece 60 with the bushing, is designated 22a.

Extending through the bushing 19 is a driving wheel shaft 23 at the inner end of which is mounted the peripherally toothed or milled driving wheel 24 which is located in a plane between 70 the cutter 1 and the body 1, for cooperative action with the edge of the cutter. Upon the outer end of the shaft 23 is a thumb and finger crank 25, the inner edge of which is shaped to form the two diametrically opposite trigger engaging 75 fingers 26.

As shown in Figure 4 the outer wing of the yoke 12 is outwardly offset to form the guide 27. In this guide is disposed the slidable trigger plate 28 which is provided with an elongated or elliptical opening 29, corresponding to the opening 9, through which the bearing 19 and collar 22 extend, so that the trigger has limited up and down movement with respect to those parts which pass through the opening 29.

Upon the lower end of the trigger plate is the laterally extending cam finger 30. This finger has cooperative action with the trigger shifting or elevating cam 31 which is secured to the outer side of the body 1 to extend obliquely with respect to the length thereof so that the trigger cam finger 30 will ride upon the inclined upper surface thereof.

The cam finger 30 of the trigger is arranged with respect to the fingers 26, to be in the path of these fingers, when the trigger plate is in its lowered position so that when the crank 25 is rotated clockwise a finger 26 thereof will engage against the cam finger 30 so that the yoke will be rocked and the toggle coupling between the yoke and the fixed pin 14 will be straightened out to raise the driving wheel 24 with respect to the cutter 7. At the same time the trigger will be shifted upwardly due to the engagement of the finger 30 upon the inclined upper face of the cam 31, until the finger 30 is inwardly of the engaged finger 26 and freed therefrom, whereupon the crank may be continuously turned.

It will be readily apparent that any excessive resistance to the upward movement of the wheel 24 will be absorbed by the spring 15 due to the fact that the downward thrust upon the yoke is transmitted through the spring to the pin 14. Such resistance is sometimes encountered, particularly if a cam rim of unusual thickness is encountered.

Figures 7 and 8 illustrate the application of a crank arm to the structure shown in Figures 1 to 4 where such structure is mounted upon a fixed bracket arm 32 which is attached to a wall or other suitable supporting structure.

The crank is indicated by the numeral 25a and is secured to the squared outer end of the shaft 23a by a suitable head rather than by the process of bifurcating the outer end of the shaft to receive the turning means, like the shaft shown in Figure 3.

In this construction the crank handle 25a carries a pin 26a for cooperation with the cam finger 30a of the trigger plate 28a. All other features of construction are the same as the structure shown in Figures 1 to 4 therefore it is believed that a further description of Figures 7 and 8 is unnecessary.

Figure 7 illustrates the yoke 12a in the position which it assumes when the driving wheel 24a is lowered for the insertion of a can rim between the wheel and the edge of the cutter. When in this position the yoke is swung counter-clockwise and the trigger plate 28a is at the limit of its downward movement. This is the position in which the parts will be left after completing a can cutting operation and removing the can from the cutter.

It will be seen that the crank carried finger 26a is in position in front of the cam finger 30a and thus when the crank is turned clockwise the finger 26a will first be brought around to engagement with the back edge of the finger 30a thereafter causing clockwise rotation of the yoke and,

as previously stated in connection with the description of the operation of the device as shown in Figures 1 to 4, causing the straightening out of the toggle connection between the yoke and the fixed pin coupling the yoke with the plate body to raise the driving wheel to operative position. The cam finger 30a will ride upon the inclined cam 31a to be raised to a position where the finger 26a will pass under the finger 30a thus permitting continued free rotation of the crank handle.

The clockwise turning of the yoke is limited by the engagement of the stop member 33, Figures 1 and 2 and 33a, Figure 7, which is carried by the yoke, with the upper edge of the C-shaped spring link therebeneath.

Figures 9 and 10 illustrate another escapement means for effecting disengagement of the trigger from the crank member in association with a rotatable yoke.

In this construction the plate body is designated 1b. At its lower end the plate has the reduced extension 34, upon the inner or cutting blade side of which is formed the flange 35 forming the can support, corresponding with the flange 18 formed upon the lower end of the link 13 of the structure shown in Figures 1 to 8 inclusive.

At its upper end the plate 1b has the inwardly turned head flange 36 with which is integrally formed the downwardly extending knife 31.

Also adjacent the upper end of the plate 1b is formed the elliptical slot 38.

The plate 1b is received between the inner and outer wings 10b and 11b of the yoke 12b, which wings are coupled together by the bearing sleeve 19c, corresponding to the sleeve 19 shown particularly in Figure 3.

Extending through the bearing sleeve 19c is the shaft 23b upon the outer end of which is secured the thumb and finger turning means or crank means 25b while upon the inner end of the shaft is secured the driving wheel 24b.

The inner wing 10b carries upon its lower edge the arm 13b with which is pivotally coupled by the pin 16b, the link 15b, the lower end of which link is pivotally coupled by means of the stud 14b, with the lower end or extension 34 of the body plate.

Upon the outer side of the body plate this stud 14b carries the cam roller 39 with which cooperates the sliding or shiftable trigger 28b which is in the form of an elongated plate and which has adjacent its upper end the elliptical slot 29b for the extension through the trigger of the shaft and bearing sleeve.

This trigger 28b is slidably mounted in the offset guide 21b which is formed in the outer wing 11b of the yoke.

The lower end of the trigger plate 28b is cut obliquely to form the cam edge 40 which is disposed in the plane of the cam roller 39 so that upon clockwise turning of the yoke and the trigger this cam edge will engage the cam roller.

Formed integrally with the plate 28b and extending outwardly therefrom adjacent the upper end of the cam edge 40, is the trigger finger 30b. This is designed for cooperative action with the fingers 26b of the crank member.

The operation of the device as shown in Figures 9 and 10 is essentially the same as that of the device shown in Figures 1 to 4, 7 and 8. When the device is in released position where it is left after removing a can therefrom, the yoke 12b will be turned counter-clockwise to the limit of its movement where the toggle connection between

the inner wing 10b and the fixed pivot 14b is broken as shown in Figure 10. The lower end of the trigger plate 28b will be free of the roller 39b and thus the trigger can slip downwardly to the limit of its movement on the bearing sleeve and shaft, bringing the finger 30b into the path of rotary movement of one of the fingers 26b.

Upon rotation of the crank 25b one of the fingers 26b will engage the finger 30b and turn the yoke clockwise thus straightening out the toggle connection and raising the driving wheel with respect to the cutter 31. At the same time the cam edge 40 will roll or slide against the cam roller 39 causing the longitudinal shifting of the trigger plate 28b until this plate reaches a position where the finger 30b is freed from its engagement with the finger 26b whereupon continued free rotation of the crank may be had.

The sides or wings of the yoke are connected, adjacent the lower edges thereof, by the transverse pin 41 which limits clockwise turning of the yoke through its engagement with the rear edge of the body plate 1b.

It will be understood that in the construction shown in Figures 9 and 10 there may be substituted for the thumb and finger crank 25b, a crank arm such as is shown at 25a in Figures 7 and 8, and carrying upon its lower end a suitable knob which may be readily grasped for rotation. Such crank means would be employed where the device is designed to be mounted upon a fixed bracket similar to the bracket 32.

In Figures 11 to 16 another construction is illustrated using essentially the same escapement mechanism as is used in the structures shown in Figures 1 to 4 and 7 to 10. However, in place of the toggle thrust connection between the yoke and the body plate for effecting the desired movement of the can and the penetration of the can head by the cutter, a novel rotatable head construction is employed which is geared to the yoke so that the turning of the yoke will turn the cutter carrying head and force the cutter into the top of the can.

Figures 11 to 14 show the application of this embodiment to a portable type opener. Here the body plate of the device is designated 1c. This plate has the lower part of the forward edge cut away to form the recess 42 and rearwardly of this recess the bottom edge has the inwardly turned can support 43. At the top of the body 1c there is formed adjacent the forward edge, the inwardly turned stop 44 which limits the rotational movement of the cutter carrying head. The head is generally designated 45 and comprises the outer gear quadrant 46, the horizontal top portion 47 and the inner depending portion 48 to which is secured, upon the side nearest the segment 46, the knife 49, the cutting edge of which depends below the lower edge of the portion 48 as shown in Figure 13. In this construction the lower and rear corner of the cutting blade is sufficiently blunt as indicated at 49' to provide traction of the driving wheel with the rim or bead of a can as the blade is rotated into position as hereinafter described.

The cutter head is pivotally secured to the inner side of the body plate adjacent the top thereof by the pivot pin 50 and when in its vertical position, to which position it is rotated for the penetration of can head by the blade, it is stopped against further turning movement by the stop 44 while its backward rotation is limited by the engagement of the yoke member, as hereinafter de-

scribed, against the forward edge of the body plate.

The numeral 12c designates the yoke, between the side wings 10c and 11c of which the body plate is disposed. This yoke has the side wings coupled together by a bearing sleeve 19d which passes through and is mounted for rotation in a suitable opening, not shown, in the body plate 1c. The yoke is disposed below the rotatable head as will be readily understood and the wing 10c has the top edge formed to provide the toothed quadrant 51, the teeth of which mesh with the teeth of the quadrant 46 as shown in Figure 11.

Through the bearing sleeve 19d is extended the driving wheel shaft 23c, upon the inner end of which is mounted the toothed driving wheel 24c while upon the outer end is secured the thumb and finger crank 25c. This crank, like the ones shown in Figures 3 and 9, has its inner edge formed to provide the trigger engaging fingers 26c.

The outer wing 11c of the yoke is offset to form the guide 27c for the sliding trigger 28c. The lower end of this trigger carries the outwardly projecting finger 30c which is near the forward edge of the trigger plate while the rear edge portion of the trigger plate is extended downwardly and is formed, at the forward edge of the extended portion, to provide the cam 40c.

The lower end of the body plate carries the outwardly directed cam flange 52 over which the cam 40c rides to shift the trigger upwardly so that the finger 30c may be disengaged from a finger 26c of the crank.

When the opener is in released position, which is the position in which the yoke is turned counter-clockwise to the limit of its movement, as it is shown in Figure 15, it is installed on the can by placing the corner of the cutter blade 49 over the rim of the can and the laterally extending stop finger 53, which is carried by the body plate and projects transversely across the back of the head, upon the rim of the can. When so placed the thumb and finger crank 25c is rotated clockwise until one of the two finger ends 26c thereof engages the outturned or outwardly directed finger 30c of the trigger. Further clockwise rotation of the crank causes the trigger and the yoke to rotate until the yoke is approximately in the position illustrated in Figures 11 to 14 at which time the trigger finger 30c escapes from the finger 26c with which it was connected due to the fact that the cam 40c has been caused to ride over the cam flange 52 thereby shifting the trigger 28c upwardly.

Since the yoke has the gear quadrant 51 in toothed connection with the quadrant 46 which forms a part of the rotatable head, the head will be caused to rotate or turn simultaneously with the turning of the yoke, to the position in which it is shown in Figures 11 and 12. The cutter blade is thus forced to pierce the end of the can and continued rotation of the crank will cause the can to be turned by the wheel 24c so that the head of the can will be cut out in an obvious manner.

It will be noted that the swinging radius of the inner edge of the finger 26c, designated by the broken line R, is such as to cause the finger 30c and the trigger 28c on which it is mounted, to be raised approximately one eighth inch between the time the finger 30c first escapes from the rear edge of the finger 26c, and the time the finger 30c is entirely out of contact with the finger 26c

during clockwise rotation of the operating handle 25c. As soon as the finger 30c is entirely out of contact with the finger 28c, gravity will cause the trigger 28c and its finger 30c to return to the position in which it is illustrated in Figure 12.

Upon counter-clockwise rotation of the operating handle 25c the finger 28c is in positive engagement with the finger 30c at all times when the inner edge of the finger 28c is above the lower edge of the finger 30c. The thickness of the finger 30c is such as to insure this positive engagement. It will be noted that such action is effected by offsetting the finger 30c from the vertical line through the axis of the shaft which supports the operating handle 25c, instead of centering the finger 30c on such a vertical line. Thus when the handle 25c is reversely rotated counter-clockwise rotation will be given the yoke 12c which will result in the movement of the cam portion 40c of the trigger from the supporting finger 52 whereby, upon again turning the handle clockwise the desired engagement of the finger 28c with the finger 30c will be obtained.

In Figures 15 and 16 the device of Figures 11 to 14 inclusive is shown mounted upon a wall supported bracket which is designated 32c and also the driving wheel shaft is shown modified in construction to have attached thereto an end of the crank handle 25d.

In this construction the top edge of the supporting bracket 32c takes the place of the cam flange 52 which is engaged by the extension finger upon the lower end of the trigger, which finger is here designated 40d while the trigger is designated 28d. Also the can guard or support, here designated 43c, serves as the upper rivet for securing the bracket 32c to the body plate 1d.

In the forms of can openers shown in Figures 11 to 16 inclusive it will be noted that complete clockwise rotation of the cutter blade is positive in relation to a relative turning of the handle or crank means thus assuring positive penetration of the end of the can by the cutter blade when the crank is rotated, and without any effort or other action on the part of the operator except the turning of the crank. Likewise, it will be noted that complete counter-clockwise turning or rotation of the cutter blade is positive in relation to a relative turning of the crank handle, thus assuring positive return of the cutter blade to full release position when the crank handle is rotated, and without any effort or other action on the part of the operator except the turning of the crank handle. This can opener provides for positive mechanical piercing of the end of the can with a minimum of effort on the part of the operator and positive mechanical releasing of the can with a minimum effort by the operator.

It will be understood that the trigger and cam mechanism illustrated in the preceding figures may be used in the construction illustrated in Figures 11 to 16 inclusive if desired. Also, the trigger and cam mechanism illustrated in the last mentioned group of figures may be used in the construction illustrated in the first group of figures. When the trigger and cam mechanism illustrated in Figures 11 to 16 inclusive are used in the construction shown in Figures 1 to 4 and 7 to 10 inclusive, the extended portion of the trigger that engages the cam would be extended and the cam surface lowered correspondingly a sufficient distance in order that the cam would not interfere with the trigger when the yoke of the device is lowered to its lowermost position.

Figures 17 to 20 inclusive illustrate another em-

bodiment of the portable can opener. This constitutes a fourth embodiment in which is employed a sliding trigger escapement carried by the rotatable yoke and as will be readily apparent substantially the same escapement mechanism is employed in this fourth embodiment as is used in the forms illustrated in Figures 11 to 16. This embodiment also employs a modification of the rotatable knife head.

10 In this fourth embodiment the body plate is generally designated 1e and has at the rear of the top edge thereof the upwardly extending ear 54 and in front of this ear there extends horizontally or laterally across the inner side of the body plate the horizontally spaced fingers 55 and 56.

Like the construction illustrated in Figures 11 to 16 the yoke 12e is pivoted to the body by the bushing or bearing sleeve 19e through which extends the thumb and finger crank supporting shaft 23e.

20 The spaced inner and outer wings 10e and 11e respectively of the yoke are coupled together by the bearing sleeve 19e and the outer wing of the yoke has the offset guide 21e in which slides the trigger 28e which, as previously stated, corresponds to the trigger mechanism of Figures 11 to 16 inclusive. The lower end of this trigger carries the camming tongue 40e which rides over the laterally extending trigger trip finger 52e carried by the body plate 1e and in front of this camming finger the trigger carries the laterally extending stop 30e which is engaged by one of the two fingers 26e which forms a part of the thumb and finger crank 25e.

30 35 The knife carrying head is in the form of a bell-crank and is generally designated 57. This is pivotally attached to the inner side of the upwardly extending tongue 54 of the body by the pivot pin 58. The upper arm of the crank is designated 59 while the downwardly extending arm is designated 60 and, as shown in Figure 18, the lower end portion of this depending arm 60 is laterally offset away from the body plate 1e.

40 45 At its free end the arm 59 of the head has secured thereto by the screws 61, the knife 62 which upon rotation of the head moves into and out of position between the fingers 55 and 56. These fingers serve, through engagement with the top edge of a can as the opener is placed in position, and cooperate with the lower finger 63, carried by the body, to maintain the device in the proper position in relation to the side of the can.

50 55 The wing 10e of the yoke has at its inner or free end the ear 64 which is offset away from the body 5e so as to be in vertical alignment with the offset lower portion of the downward extension 60 of the head.

60 65 Interposed between the offset lower portion of the extension 60 and the ear 64, and the adjacent body, is a coupling link 65, one end of which is pivotally attached to the ear 64 by the pin 66, while the other end is pivotally attached by the pin 67 to the offset lower end portion of the extension 60 of the head. The space between the body plate and the ear 64 and offset lower end of the extension 60, is just sufficient to snugly receive the coupling link 65 and therefore the link is securely maintained in position upon the pins 66 and 67.

70 75 The can flange engaging wheel is designated 24e and is, of course, carried by the shaft 23e to be rotated thereby.

Figure 21 illustrates the same embodiment illustrated in Figures 17 to 20 inclusive, constructed with an extension arm 68 by which the embodiment may be mounted upon, or by means of, a

11

suitable wall attached bracket. This illustration also discloses the use of a crank arm or operating handle bearing a knob, not shown, at its outer end for effecting the rotation of the driving wheel shaft, such crank handle being designated 69. The crank handle carries upon its inner side the trigger engaging finger 70 which functions in the same manner as the fingers 26₂ of the thumb and finger crank 25_e.

Figure 18 illustrates the device of the fourth embodiment in released position, that is, the position in which it is ready for application to, or to receive, a can. Figure 17 is, of course, a view of the opposite side of the device from that shown in Figure 18 and Figure 17 shows the relation of the parts of the device when in operating position.

If the device is not already in the position illustrated in Figure 18 the operator lifts the opener by the arm 59 of the bell crank. This causes the opener to assume the position in which it is shown in Figure 18. When in this position the device is placed on the can with the two fingers 55 and 56 resting on the rim or flange of the can. The opener is then moved toward the can until the driving wheel 24_e is against the side of the can. When in this position the end of the arm 59 which carries the cutter 62 is forced downward until the cutter is near the end of the can and on the inside of can rim or flange. The thumb and finger handle 25_e is then rotated clockwise causing the trigger 28_e, which will be engaged by the handle finger 26_e, the yoke and the bell crank arm to be rotated until the cutter has penetrated the end of the can. When this action has been effected and the cutter has penetrated to the predetermined depth, the trigger escapes from connection with the handle finger 26_e by the cam 40_e riding over the trip finger 52_e, thus permitting the handle to be continuously rotated clockwise until the end of the can has been cut out.

The opener is so designed that when the trigger has escaped from the finger 26_e of the handle, the axis of the pin 66 is below a straight line connecting the axis of the rivet pin 67 and the axis of the shaft 23_e of the driving wheel. Therefore the thrust against the end of the cutter 62 would tend to cause the yoke to rotate further clockwise. However, further clockwise rotation beyond a predetermined point is prevented by the inner side of the yoke engaging the lower side of the finger 55.

Figure 22 illustrates the fifth embodiment in which the knife carrying head slides or moves vertically across the inner side of the body plate 1_f. The escapement mechanism in this figure and in the succeeding figures has not been illustrated as such mechanism may be of exactly the same design as that shown in connection with the fourth embodiment and the embodiment illustrated in Figures 11 to 16 inclusive.

The body plate at the top edge has the laterally inwardly directed spaced fingers 55_a and 56_a while at the lower end of the plate is the laterally inwardly extending finger 63_a which coacts with the upper fingers for maintaining the device in the proper position against the side of a can, and the oppositely directed outwardly extending trip finger 52_f with which the cam point, not shown, of the trigger, not shown, engages.

The yoke 12_f is pivotally coupled to the body plate by a bearing sleeve, not shown, but of the same design and joining the two sides of the yoke in the same manner as the sleeve 19_e while the driving wheel, which is designated 24_f, is carried upon the operating shaft, not shown, in the same manner as in the other embodiments.

12

In this fifth embodiment there is disposed against the inner side of the body plate 1_f, the elongated slide plate 71 at the upper end of which is the knife supporting head 72 which is of the same design as the head shown in Figure 3. This slide 71 and the head, are snugly engaged between the fingers 55_a and 56_a and the lower end portion of the slide has the longitudinally extending elliptical slot 73 therein, through which extends the bushing which couples together the inner and outer wings of the yoke 12_f. The slide 71 moves between the inner wing 10_f of the yoke and the adjacent face of the body plate and its up and down movement is controlled by the movement of the yoke 12_f.

Extending downwardly from the lower edge of the wing 10_f of the yoke is the ear 74 with which is pivotally coupled by the pivot pin 75, the lower end of a substantially C-shaped link 76. The upper end portion of this link is turned to extend across the top of the body plate substantially parallel therewith and is pivotally attached by the pivot pin 77 with the upper end portion of the knife head carrying slide 71. As shown the upper end of the link 76 is above the ear 56_a.

It will be readily apparent from the foregoing that in the use of the fifth embodiment when the yoke 12_f is rotated counter-clockwise the ear 74 will swing around to move the link 76 upwardly and thus shift the slide 71 so as to separate the knife, not shown, from the driving wheel 24_f. The device may then be applied to a can in the same manner as the previously described embodiments and when the yoke is then turned clockwise through the medium of the operating handle, not shown, the link 76 will be pulled down to force the knife, not shown, into the head of the can whereupon the trip mechanism, not shown, will release the handle and permit the continued clockwise rotation thereof until the head of the can is removed.

Figure 23 illustrates the sixth embodiment wherein is shown another means of actuating the knife head carrying slide. In this embodiment the body plate is designated 1_g while the lateral inwardly extending ears at the top edge thereof are designated 55_b and 56_b.

In this embodiment the knife head carrying slide plate is designated 71_a while the knife head is designated 72_a, the knife not being shown.

The yoke is designated 12_g while the driving wheel which is carried by the bearing sleeve, not shown, which couples the two sides of the yoke together, is designated 24_g. At the lower end of the body plate is the laterally extending finger 63_b which cooperates with the fingers 55_b and 56_b and extending outwardly in the opposite direction from the finger 63_b is the stop finger 52_g for coaction with the trip mechanism, not shown, in a manner which will be readily understood from the description of the preceding embodiments of the invention.

The slide plate 71_a is of a length to extend down beyond the lower end of the body plate and is cut out to provide the two spaced furcations 78 between which is engaged the lower can guide finger 63_b. This finger thus serves the secondary function of guiding the plate 71_a in its longitudinal movement, in association with the upper fingers 55_b and 56_b.

In the plate 71_a is the elongated slot 73_a through which extends the bearing sleeve, not shown, which is carried by the yoke and on which the plate has vertical movement.

Beneath the slot 73_a the plate 71_a has formed

therein the transversely extending slightly arcuate cam slot 79 and operatively engaged in this slot is the cam follower pin 80 which is secured to the depending ear 14a which forms an integral part of the bottom edge of the inner wing 10g of the yoke.

It will be readily apparent from the foregoing description of the embodiment illustrated in Figure 23 that upon counter-clockwise rotation of the yoke the cam follower pin 80 will be swung in an arcuate path around the turning axis of the yoke and will cause the knife head carrying plate 11a to shift upwardly to move the knife, not shown, away from the driving wheel 24g. The opener is then placed in position upon the can and upon clockwise turning of the yoke the cam follower pin 80 will force the slide 11a down to cause the knife, not shown, to penetrate the head of the can whereupon the trip mechanism, not shown, will function to release the operating handle, not shown, so that the latter may then be continuously turned to cut out the head of the can.

Figure 25 illustrates a seventh embodiment of the opener, the view being of the inner side thereof. In this embodiment another form of thrust means for the operation of the knife head carrying slide plate is shown. The body plate in this embodiment is designated 1h and has at its top edge the lateral inwardly directed guide fingers 55c and 56c while at the lower edge and adjacent the front edge is the lateral inwardly extending finger 63c. This finger together with the inwardly extending finger 81 which is at the back edge of the body plate and above the bottom edge thereof, cooperate for the longitudinal guidance of the knife head slide plate 11b. The knife head of this plate is designated 12b, the knife not being shown.

The plate 11b is of materially greater length than the body 1h as shown and is guided at its upper end between the fingers 55c and 56c while its lower end extends beyond the lower edge of the body plate between the fingers 63c and 81 as previously stated.

The yoke is designated 12h while the driving wheel is designated 24h.

The knife head slide plate 11b has the longitudinal elliptical slot 73b therein through which extends the yoke carried bearing sleeve, not shown, as in the other embodiments.

Extending downwardly from the lower edge of the inner wing 10h of the yoke is the ear 14b which at its lower end is turned to extend laterally as indicated at 82 to provide the can guide which cooperates with the fingers 55c and 56c in properly locating the opener upon the side of a can.

The ear 14b is offset away from the body plate 1h so that there may be extended between it and the slide plate 11b the upper end of a thrust link 83 which is pivotally attached to the ear as indicated at 84 while the lower end of this link is pivotally attached as at 85 to the lower end of the knife head carrying slide 11b.

It will be readily apparent that when the yoke 12h of this seventh embodiment is swung down in counter-clockwise direction the depending ear 14b will swing around and pull up the plate 11b, by the link 83, thus shifting the knife, not shown, away from and to inoperative position with respect to, the driving wheel 24h. The cutter is then placed in position upon the can like the previously described embodiments and reversed rotation of the yoke will thrust the link 83 down-

wardly and force the slide plate 11b to move down so as to cause the knife, not shown, to penetrate the head of the can.

Figure 24 illustrates a modified construction of the C-shaped link such as illustrated in Figure 22, whereby slight relative movement between the ends of the link, may be effected for the relative adjustment of the can driving wheel 24i and the lateral fingers 55d and 56d. As will be seen the link which is here designated 16a is provided at a suitable point in its outer edge with the transversely directed slot 86 and into a suitable tapped opening, not illustrated, through which the slot 86 passes, there is fitted the tapered screw 87. It will be readily apparent that by threading this screw inwardly the opposing edges of the slot 86 will be forced apart thereby slightly flexing the link in a manner to bring the pivoted ends 15a and 11a together slightly. It will be readily apparent that with this arrangement a slight adjustment may be made between the driving wheel 24i and the fingers 55d and 56d.

In Figures 26 and 27 there is illustrated a modified construction of the thrust spring shown in the first embodiment of the can opener as illustrated in Figures 1 to 8 inclusive. The same means is shown in connection with this modified spring structure for varying the distance between the ends thereof as shown in connection with the link 16a of Figure 24.

The spring of Figures 26 and 27 is generally indicated by the reference numeral 88 and is substantially C-shaped and has the inturned end portions 89 which are coupled between the thrust members of the can opener mechanism.

The two spaced side portions 90 of the spring carry the inwardly extending lugs 91 which come into relatively close spaced opposed relation. These lugs at their opposed ends are drilled and tapped as indicated at 92 to receive the tapered screw 93 which connects across the gap between the lugs 91 as shown clearly in Figure 26. As in the construction illustrated in connection with the link 16a it will be readily seen that if the screw 93 is threaded inwardly its tapered form will cause a separation of the lugs 91 and consequently a separation of the opposed end portions 89 and thus, when the spring is used in an opener of the character shown in Figures 1 to 4, it will be readily seen that the yoke and the parts carried thereby will be shifted toward the upper or head end of the device so that greater pressure of the driving wheel 24 against the rim or flange of the can is effected.

In Figure 28 there is illustrated in side elevation the right or outer side of an alternate escapement mechanism to that illustrated in Figure 9 of my Patent No. 2,411,449.

In this escapement construction where the body plate is designated 94, the arm 95 is secured to any suitable thrust mechanism such as is illustrated in the present application and the pending application above referred to. Such thrust mechanism may be the eccentric wheel structure illustrated in my prior patents and application or the toggle thrust mechanism shown in such prior application.

In the present escapement structure the outer side of the body plate 94 carries the forwardly and upwardly curving cam track 96 with which cooperates the follower pin 97 which is carried by the slide plate 98 which is housed in the upper part of the arm 95, such upper part of the arm having the inwardly extending longitudinal edge 70 flanges 99 which join with the spaced back por-

tions 100 to form the guide for the pin-carrying slide plate.

This slide plate 98 carries at its lower end and adjacent the rear edge the latch finger 101 and the plate is normally urged outwardly toward the free end of the arm by the spring 102 which is housed in the guide between the upper end of the slide plate and the top portion of the arm.

Adjacent to the other end of the arm there is secured, upon the inner side of the arm, the rivet 103 which pivotally supports in the same vertical plane with the latch plate or slide plate 98, an oscillatable trigger 104 which projects as illustrated, beyond the free end of the arm.

The upper or inner end of the trigger 104 is extended at its forward edge to provide the finger 105 which cooperates with the latch finger 101 in the manner about to be described.

The numeral 106 designates the operating crank or handle which is connected with the shaft 107 by which the driving wheel, not shown, is rotated. This handle carries upon its inner side the trigger engaging pin 108 for connection with trigger 104.

The trigger 104 is illustrated in the escaping position. It will be seen that the arm 95 has been rotated clockwise simultaneously as the crank arm or operating handle 106 was so rotated, by engagement of the pin or lug 108, with the outer end of the trigger 104. It will be seen that after the arm 95 has been rotated clockwise to approximately the illustrated position, the cam track 96 will have forced the latch plate 98 inwardly until the trigger 104 will escape from such latch and further clockwise rotation of the crank 106 will cause the trigger 104 to rotate clockwise on its pivot 103 until approximately in the position illustrated in dotted outline. At this time the trigger 104 escapes from the pin or lug 108 and gravity causes the trigger 104 to rotate counter-clockwise on its pivot 103 until approximately in the position shown in solid lines. Further counter-clockwise rotation of the trigger 104 on its pivot is prevented by its engagement with the portion 109 and the extended portion of the front flange 99 which forms a part of the arm 95.

During counter-clockwise rotation of the crank arm 106, the pin 108 will engage the opposite side of the trigger 104 causing the arm 95 to rotate therewith. As soon as the arm 95 has been rotated sufficiently counter-clockwise to permit the latch 98 to be moved outwardly by the spring 102 until the trigger 104 will not be in escaping position, the trigger cannot be rotated either clockwise or counter-clockwise on its pivot. Consequently the trigger 104 acts as a fixed part of the arm 95 at all times except when in escaping position.

At all times when the pin 97 is not in engagement with the cam 96 the inner end of the trigger 104 and the opposing face of the latch finger 101 are maintained in cooperating connection by the spring 102.

Figure 29 illustrates a modification of a knife head construction such as is illustrated in Figures 2 and 8 of the present application and in Figure 21 of Patent No. 2,314,506.

In this head construction the head is generally designated 110 and is supported upon the upper end of the body plate 111. The upper end of the body plate has the laterally turned portion 111a from which is struck upwardly the vertical plate 112 thus providing at each side of the plate a guide finger 113, one only of which is illustrated in this figure.

The upwardly extending plate portion 112 enters into the square inverted U member 114. This member comprises the front and back legs 115 and 116 respectively, the back leg having secured thereto by the screws 117, the upturned plate 112 while the front leg, which extends at its lower end between the guide fingers 113, has secured thereto by the screws 118, the knife blade 119 which projects downwardly between the members 113 as illustrated. The blade is thus located between the legs of the member 114 by which it is protected as shown.

It is to be understood that in any embodiment of the present application or prior applications or patents in which this inverted square U-shaped head is used, the desired proximity of the cutter blade 119 to the driving wheel, not shown, may be adjusted at the time of manufacture or at any subsequent time, by the insertion of suitable shim or shims between the cutter blade 119 and the depending portion of the member 114 to which it is secured.

Figures 30 and 31 illustrate a modified thrust block and spring support for a toggle link thrust mechanism such as is illustrated in my prior Patent 2,314,506, Figures 28 and 29.

In this modified arrangement the numeral 120 designates the body plate of the device while the numeral 121 generally designates the lower end portion of the toggle link which is operatively coupled with a rotatable yoke such, for example, as illustrated in the present application in Figures 1 and 2 or other figures where the yoke is shown. The lower link of the toggle thrust mechanism is designated 122 and as shown, this has an upper portion 122a which lies against the left hand or inner side of the body plate between the offset lower portion 121a of the upper link and the body plate, and is pivotally coupled to the lower end of the upper link by the rivet 123. The lower half of the lower toggle link 122 is inwardly offset from the left hand side of the body plate 120, as indicated at 122b and has formed therethrough the short vertically disposed elliptical opening 124.

At each longitudinal edge the lower portion 122b of the lower link 122 has the laterally turned ears 125 which are directed toward the body plate.

The lower end of the lower toggle link 122 is connected for limited up and down movement, with the body plate 120, by the pivot pin 126 which is secured to the body plate and extends through the elliptical opening 124, as shown in Figure 31.

Supported upon the pin 126 in the space between the offset lower portion 122b of the lower toggle link and the body plate 120, and between the ears 125, is the spring supporting block 127 upon the top edge of which is mounted the spring 128 which is held between the block and the overlying portion 122a of the lower toggle link.

It will be readily apparent upon examination of the Figures 30 and 31 that in this construction as in the construction illustrated in the patent referred to, if unusual resistance is encountered, the toggle link will bear upon the rivet pin 126 after the spring 128 has been compressed to its predetermined extent.

Figure 32 illustrates another form of the escapement mechanism. The structure here shown constitutes a modification of the rotatable yoke which is illustrated in the majority of the previous figures, wherein there is mounted upon the yoke a pivoted trigger which in rotating through

a short arc functions in the same manner as the sliding or reciprocating trigger of the previously illustrated and described structures.

In this modified construction the body plate is designated 129. This has extending transversely therethrough and supports the shaft 130 upon which is supported for rocking movement the yoke 131 which corresponds in construction to the yoke 12 of the opener illustrated in Figures 1 to 4 and other figures of this application and has, like the yokes of the other figures, two parallel plates, one only of which is shown. The illustrated plate of the yoke 131 is designated 132. Between these spaced plates the body 129 positions. The bushing with which the two side plates of the yoke are connected and through which the shaft 130 extends for free rotation, is shown in dotted outline and designated 133.

The operating handle for the shaft and by which the rotation of the yoke 131 is accomplished, is designated 134 and is of the same form as the handle shown in Figure 3. It will be understood, however, that this handle may be replaced by a crank if desired.

At the lower edge of the side plate 132 of the yoke is a downwardly extending ear 135 which is pivotally connected by the rivet 136, the trigger 137. This trigger has a relatively wide free end in which is formed the elliptical slot formed on an arc struck from the center of the pivot 136, such slot being designated 138. The slotted free end of the trigger 137 is disposed between the plate 132 and the handle or crank 134 and the shaft and bushing 130 and 133 respectively pass through this arcuate slot.

The lower edge of the trigger 137 carries the outwardly extending trip finger 139 which is arranged to be engaged by the fingers of the crank 134 upon clockwise or counter-clockwise turning of the crank.

Secured to the outer side of the body plate 129 below the shaft and in position to be engaged by the lower edge of the trigger at the inner end of the finger 139, is the obliquely directed cam 140.

Mounted upon the shaft 130 is a flat washer 141 which fits closely between the outer end of the bushing 133 and the inner end of the handle 134. This washer keeps the rotatable end of the trigger 137, in alignment at all times but permits free rotation of the trigger on its pivoting rivet 136.

It will be readily apparent that when the yoke 131 has been rotated counter-clockwise to the limit of its movement where the implement is ready to receive a can, upon clockwise turning of the handle 134 one of the fingers, not shown, thereof, corresponding to the fingers 26 of the structure shown in Figure 3, will engage the finger 139 and cause the yoke to swing clockwise in the desired manner. When the yoke has swung in this direction to a predetermined extent the lower edge thereof at the inner end of the finger 139 will ride up upon the top surface of the cam 140 to a position where the handle will be released from the finger whereupon continued clockwise turning of the handle may be had. Upon reverse rotation of the handle the finger of the handle will engage the finger 139 upon its forward edge and the yoke will then be swung back in a counter-clockwise direction to the inoperative position of the implement.

I claim:

1. A rotary drive wheel type can opener comprising a body having a longitudinal opening, a

- cutter carried by the body, a rotary shaft extending through the body opening for movement lengthwise of the body, a member rotatably supported on the shaft, a driving wheel carried by the shaft for rotation thereby and for coaction with the cutter, means connected with and actuated by said member upon rotation thereof for effecting translational movement of the wheel and cutter, means for turning the shaft and wheel independently of the rotatable member, a trigger element slidably connected with and carried by the rotatable member for rectilinear movement, means for limiting said rectilinear movement, means for forming a driving connection between the trigger element and the shaft turning means upon turning the turning means to rotate the rotatable member, and means for releasing the trigger element from the shaft turning means upon rotation of said rotatable member in one direction to a predetermined extent.
2. A rotary drive wheel type can opener, comprising a body, a cutter member carried by the body, a member carried by the body for rotation, a can rim engaging wheel rotatably carried by the rotatable member for coaction with said cutter member, means supporting one of the members for translational movement relative to the other to change the working distance between the members, means operating upon rotation of the said rotatable member for effecting said change in the working distance between the cutter and wheel members, turnable means connected with the rotatable member for turning the wheel, a trigger slidably connected with and supported on the rotatable member for rectilinear movement and for movement by said turnable means to effect a desired change in the said working distance between the cutter and wheel members, means for limiting the rectilinear movement of the trigger, and means for releasing the trigger from the turnable means after a predetermined rotation of the rotatable member in one direction to permit continued independent turning of the turnable means and of the wheel.
3. A rotary drive wheel type can opener as set forth in claim 1 in which the trigger releasing means comprises a pair of cooperating camming elements one of which is carried by the body and the other one of which is carried by the sliding trigger whereby the sliding movement of the trigger out of engagement with the shaft turning means is effected when said camming members come together.
4. A rotary drive wheel type can opener, comprising a body having a longitudinal opening, a cutter carried by the body, a rotary shaft extending through the body opening for movement lengthwise of the body, a member rotatably supported on the shaft, a driving wheel carried by the shaft for rotation thereby and for coaction with the cutter, means supporting the member for rectilinear movement relative to the cutter, means connected with and actuated by said member upon rotation of the member for effecting said relative movement, means for turning the shaft and wheel independently of the rotatable member, a finger carried by the shaft turning means, a trigger member slidably connected with and carried by the rotatable member for limited rectilinear movement, a stop finger carried by the trigger member for engagement with the first finger upon the turning of the shaft turning means in one direction to establish a driving connection between the trigger and the shaft turning means, a fixed element carried by the

body, and said stop finger being adapted to contact the fixed element upon turning of the rotatable member and the shaft turning means to a predetermined extent in one direction and have a camming action by which the stop finger is shifted out of engagement with the first finger.

5. A rotary can opener of the character set forth in claim 4 in which the said means for releasing the trigger from the shaft turning means comprises an edge of the trigger extending obliquely to the length of the trigger and a fixed camming member carried by the body in the path of movement of said oblique edge when the member and the shaft turning means are turned as a unit.

6. A rotary can opener comprising a body having an opening, a cutter carried thereby, a rotary shaft extending through the body opening, a member rotatably supported upon the shaft, a driving wheel secured to the shaft for rotation thereby and for coaction with the cutter, the member for movement relative to the cutter, a resilient coupling between the member and the body forming a thrust means whereby movement of the member and the wheel is effected upon the rotation of the member in one direction, a trigger, means supporting the trigger on the member for limited rectilinear sliding movement transversely thereof, means for turning the shaft and wheel independently of the rotatable member, means to establish a drive connection between the shaft turning means and the member in turning the shaft turning means in one direction to effect movement of the wheel relative to the cutter, and a camming means carried by the trigger and the body functioning to disengage the trigger from shaft turning means upon rotation of the member in one direction to a predetermined extent.

7. A rotary can opener comprising a body having an opening, a cutter carrying head, a rotary shaft extending through the body opening, a member rotatably supported on the shaft, a driving wheel carried by the shaft for rotation thereby, said head being pivotally coupled with the body, a driving coupling between the head and the rotatable member by which relative movement is effected between the cutter and the driving wheel upon rotation of the rotatable member, means for turning the shaft and wheel independently of the rotatable member, a trigger member slidably carried by the rotatable member, means for establishing a driving connection between the trigger and the shaft turning means upon turning of said turning means to rotate the rotatable member, and means operating to release the trigger from the shaft turning means upon rotation of the said rotatable member in one direction to a predetermined extent.

8. A rotary can opener as set forth in claim 7 in which the said driving connection between the pivoted head and the rotatable member comprises connected gear segments.

9. A rotary can opener as set forth in claim 7 in which the said driving connection between the pivoted head and the rotatable member comprises a coupling link.

10. In a rotary can opener of the character set forth, an escapement mechanism between two concentrically pivoted members, comprising a body, an arm supported at one end by the body for rotation, a crank supported for turning around the rotary pivot of and to move across and in close proximity to the arm, a latch member supported by the arm for movement longitudinally thereof, resilient means constantly urg-

ing movement of the member toward the free end of the arm, a trigger pivotally mounted on the arm for rotation on an axis perpendicular to the arm, a member carried by the crank for connection with the trigger upon rotation of the crank clockwise and counter-clockwise, means for establishing a latching connection between the trigger and the latch member for holding the trigger against swinging upon the turning of the crank in one direction to engage the said member with the trigger, whereby the crank and arm are coupled to turn together, and means operating upon movement of the crank and arm together beyond a predetermined position in the said one direction to effect the shifting of the latch member against the action of the resilient means and the breaking of said latching connection whereby the trigger may rotate and free the crank for continued turning in the said one direction independently of the arm.

11. In a rotary can opener of the character described, a body member, a pair of thrust links having pivotally coupled ends and disposed at one side of the body, one of said links being adapted for connection with a force applying means carried by the body, and the links being arranged to extend lengthwise of the body whereby a thrust applied to and longitudinally of the said one link will be transmitted to and lengthwise of the other link, the said other link being offset through a portion of its length from the body at the end remote from the said one link and forming an under-cut shoulder, the said offset end having a longitudinally extending elliptical slot therein, a pivot pin carried by the body and engaged in said slot, a block supported on the pin between the offset and the body and spaced from said shoulder but in opposed relation with the shoulder, and a spring interposed between the block and the shoulder and resisting movement of the said other link in one direction.

12. A rotary can opener of the character set forth in claim 11, in which the said offset end of the other link has bordering ears at its longitudinal edges extending toward the body across the adjacent ends of the block to maintain the block and spring in position beneath the shoulder.

13. A rotary can opener, comprising a body member, a cutter carried by the body, a rotary can driving wheel supported upon the body for movement relative to the cutter, a crank for turning the wheel, a thrust means connected between the body and said wheel for effecting relative movement between the wheel and cutter, an arm operatively coupled with said thrust means for turning on the axis of said wheel to actuate said thrust means, a trigger supported upon the arm for movement in a line perpendicular to said axis, said trigger normally tending to move in one direction in said line, means carried by the crank for connection with the trigger for effecting turning movement of the arm and crank as a unit for a predetermined distance in a circular path around said axis, camming means supported upon the body, and means carried by the trigger for engagement with said camming means to effect movement of the trigger in the opposite direction at the limit of said predetermined movement of the arm and crank to effect disengagement of the trigger from the crank carried means.

14. A rotary type can opener, comprising a body, a cutter carried by the body, a rotary can driving wheel supported upon the body member

for movement relative to the cutter, a crank for turning the wheel, a thrust means connected between the body and said wheel for effecting relative movement between the wheel and the cutter, an arm operatively coupled with said thrust means for turning on the axis of said wheel to actuate said thrust means, a trigger supported upon the arm for limited rectilinear movement in a line perpendicular to said axis, resilient means normally urging movement of the trigger in said line away from said axis, means carried by the crank for connection with the trigger for effecting movement of the arm and crank as a unit for a predetermined distance through a circular path, camming means supported upon the body, and means carried by the trigger for engagement with said camming means to effect movement of the trigger in the opposite direction at the limit of said predetermined movement of the arm and crank, to disengage the trigger from the crank carried means.

15. A rotary can opener, comprising a body, a cutter carried by the body, a rotary can driving wheel supported upon the body for movement relative to the cutter, a crank for turning the wheel, a thrust means connected between the body and said wheel for effecting relative movement between the wheel and the cutter, an arm operatively coupled with said thrust means for turning on the axis of said wheel to actuate said thrust means, a trigger supported upon the arm for limited rectilinear movement in a line perpendicular to said axis, spring means normally urging movement of the trigger in said line away from said axis, a member pivotally supported upon the arm and normally engaged by said trigger under the action of said spring means to be held from turning, means carried by the crank for connection with said pivoted member to effect turning movement of the arm and crank as a unit for a predetermined distance in a circular path around said axis, a camming plate carried by said body, and a cam follower element carried by the trigger for engagement with said camming plate to effect movement of the trigger in the opposite direction at the limit of the said predetermined movement of the arm and crank, to effect disengagement of the trigger from the said pivoted member and release of the crank for free rotation.

16. In a rotary can opener, a body, a cutter carried thereby, a member carried by the body for rotation, a can rim engaging wheel rotatably carried by said member for co-action with said cutter, means operating upon rotation of said member for relatively moving the cutter and wheel, turnable means connected with the rotatable member for turning the wheel, said member having an offset portion forming a guide, a trigger plate slidably mounted in said guide for rectilinear movement, means for limiting the rectilinear movement of said trigger plate, a cam finger carried by the trigger plate, means forming a part of said turnable means for engagement with said cam finger, and a camming plate carried by the body member and adapted to be engaged by said cam finger upon rotation of the finger and the rotatable member to effect the disconnection of the cam finger from said turnable means.

17. In a rotary can opener, a body, a cutter carried thereby, a member carried by the body for rotation, a can rim engaging wheel rotatably carried by said member for co-action with said cutter, means operating upon rotation of said member for relatively moving the cutter and wheel, a crank connected with the rotatable member for turning the wheel and having rotation independently of the rotatable member, said rotatable member being formed to provide a guide, a trigger plate supported in said guide for rectilinear movement, means for limiting the rectilinear movement of the trigger plate, said trigger plate having an end provided with an extension formed to provide a camming surface, a finger carried by the trigger plate and extending at right angles to the line of movement of the plate, means carried by the crank and adapted to engage said trigger plate finger when the trigger plate is in one position whereby to effect the turning of the rotatable member and crank as a unit, and a camming member carried by the body member and extending laterally therefrom to be engaged by the camming surface of the trigger plate extension to effect movement of the trigger plate in one direction and release of the connection between the crank and trigger plate.

18. A rotary drive wheel type can opener, comprising a body plate having an opening therethrough, a yoke having two spaced side portions between which the body plate is positioned and a cross connecting portion between the side portions, the yoke side portions having aligned openings with which the plate opening is aligned, a shaft rotatably supported in and passing through said aligned openings, the shaft connecting the two sides of the yoke through the body plate opening, a can rim flange engaging wheel element secured on one end of the shaft, crank means on the other end of the shaft for turning the latter, a cutter element supported upon the body plate upon the side thereof adjacent to said wheel for coaction with the wheel, means permitting movement of one of the coacting elements into and out of coacting relation with the other element, said yoke being oscillatable to one position when the elements are in coacting relation and to a second position when the elements are out of such relation, cooperating members connected with the yoke and crank means which engage one another when the crank is rotated in one direction when the elements are in said second position to turn the yoke on the shaft and move the elements to the said one position, and means functioning to separate the engaged members when the elements have assumed the said one position.
